UNITED STATES PATENT OFFICE.

ALLISON J. THOMPSON, OF CLEVELAND, OHIO.

LAMP HANGER.

Application filed February 23, 1923. Serial No. 620,802.

This invention relates to improvements in lamp hanger structures.

The object of this invention is to provide an improved means for making electric contact between the upper and lower hanger members of a lamp hanger structure so as to insure effective engagement between the contact members.

More particularly it is the object of this invention to provide a resilient means for supporting the contacts on one of the hanger members and at the same time serving to produce effective engagement with the contacts on the other member.

It is also an object of this invention to provide such an improved means of electric contact in which the parts are readily separable and also standardized to a certain extent so as to facilitate the removal and renewal at a comparatively low cost.

Fig. 1 is a vertical section taken through a lamp hanger structure embodying my present improvement and showing the parts locked together; Figs. 1^a and 1^b illustrate different positions of the resilient supports for the electric contacts during manipulation of the lower hanger member; Fig. 2 is a transverse section taken on line 2—2 of Fig. 1; Fig. 3 is a detail view taken on line 3—3 of Fig. 2; Fig. 4 is an end view of one of the lower contact members; Figs. 5 and 6 are detail views of one of the insulator blocks; and Fig. 7 is an inverted plan view of one of the upper contacts.

The general type of lamp hanger illustrated in the present case is substantially the same as that shown in my copending application, Serial No. 608,446, filed December 22, 1922, to which reference may be had for a clearer understanding of the same.

Upon the top of the canopy member 1 of the main hanger member there is supported the sheave housing 2 in which is mounted the sheave 3 for the cable 4. This structure is supported by means of the ears 5 and the lower part of the sheave housing is secured to the top of the canopy by means of screw bolts 6 which serve also to secure the slotted tubular member 7 upon the inside of the canopy 1. As will be more clearly understood from the copending application above referred to, the tubular member 7 is provided with notches on opposite sides of its slot for locking engagement with the dog 8 which is pivotally mounted upon the stem 9 carried by the lower hanger member and adapted for insertion up into the tubular member 7. In this manner, the

lower hanger member is suspended from the upper hanger member, and the engagement of the dog 8 with the tubular member 7 is controlled by means of the cable 4 which has its lower end knotted as indicated at 10 for raising and lowering the lower hanger member, as will be more clearly understood from the application above referred to.

The insulator blocks 11 are secured to the top wall of the canopy 1 by means of the screw bolts 12, and have anchored therein the upper ends of the bolts 13 which carry the upper contact members 14. Each of the contact members 14 has a concave contact surface which is curved in one direction and is provided with a countersunk opening for seating of the head of the bolt 13, as clearly indicated in Fig. 1. The heads of the bolts 13 are also curved so as to conform to the curvature of the contacting surface of each of the contact members 14. Suitable washers are provided, as for instance, the fiber washer 15, and the brass washers 16 between which the lead wire 17 is adapted to be clamped. The lead wires 17 are led into the lamp hanger in the same manner as indicated in the copending application above referred to.

The lower contact members 18 are formed with upper convex surfaces curved in one direction for contact engagement with the correspondingly formed surfaces of the contact members 14 and are seated in the cut out portions 19 provided in the insulator sections 20. The lower insulator sections or blocks 21 are duplicates of the upper insulator blocks 20 and each of these two insulator blocks in each case is provided with a groove 22 of semi-circular cross section, as indicated in Fig. 5, and of a substantially U-shaped configuration somewhat restricted at its ends, as clearly indicated in Fig. 6 of the drawings. The insulator blocks or sections 20 and 21 are clamped together by means of the bolts 23 which extend through central openings therethrough and have their heads engaging in suitably provided countersinks in the top of the lower contact members 18, as clearly indicated in Fig. 1. The tops of the heads of the bolts 23 are given a convex curvature in one direction corresponding to the curvature of the top surfaces of the contact members 18. Suitable washers are provided for the lower ends of the bolts 23 so as to constitute a binding post connection for the lead wires 24 which connect with the lamp. In the present case, I have adopted

the fiber washer 25, seated in the cut out portion 19; and the brass washers 26 between which the lead wires 24 are clamped by means of the brass nuts 27. The insulator blocks 20 and 21, when clamped together in the manner just described, are supported by means of the laterally extending looped spring wire members 28, which have their middle portions formed in a substantially U-shape corresponding to the shape of the groove 22, and are adapted to seat in said grooves between the insulator blocks 20 and 21, as clearly indicated in Fig. 1. The two arms of the looped wire members 28 are formed as coils 29 and 15 are adapted to be engaged over the projecting studs 30 for support thereupon. These studs are integral with the base portion of the post member 9 of the lower hanger member and have their inner sides beveled or cut 20 away, as indicated at 30', so as to facilitate the engagement or mounting of the coil portions 29 thereupon. The free ends 31 of the wire members may be anchored in any suitable manner and are here shown as extending 25 between the shoulders 32 and the upstanding ribs 33 formed as part of the base portion of the stem member 9 of the lower hanger member.

An outlet member 34 is screw threaded into 30 the bottom end of the post member 9 and is provided with openings 35 through which extend the lead wires to the lamp which in turn is supported upon the screw threaded end portion 36. The closure member 37 is 35 provided for the canopy member 1 and is held in engagement with the bottom edge of the canopy member by means of the nut 37' and the spring 38 engaging the lower central portion of the closure member 37, which in turn 40 surrounds the outlet member 34.

The parts are so constructed and arranged that, by virtue of the spring nature of the wire members 28, the insulator members 20 and 21 together with the lower contact members 18 will extend upwardly at an angle 45 when the lower lamp hanger member is in lowered position, as illustrated in Fig. 1^a. Then, upon raising the lower hanger member so as to engage the same with the upper hanger member, the lower contact members 18 will 50 be brought into effective wiping engagement with the upper contact members 14, during which engaging action the spring wire members 28 will permit the parts carried thereby 55 to be rocked so as to extend downwardly at an angle as illustrated in Fig. 1^b and thereby permit the dog 8 to be raised past the notches preparatory to seating in the same. As more 60 fully explained in the application referred to, the cable is then released and the dog member 8 rolls into locking engagement with the notches of the tubular member 7. As soon 65 as the upper and lower lamp hanger members are thus effectively locked together, the parts carried by the spring wire members 28 will

assume substantially horizontal position, as illustrated in Fig. 1, which position they will continue to occupy so long as the parts are in locked engagement, and the contacts are maintained in effective engagement by the 70 tension of the spring members 38. Then, upon raising the lower hanger member so as to roll the latch member 8 out of engagement with the tubular member 7, the spring wire members 28 will permit the parts carried thereby to again rock downwardly to the position illustrated in Fig. 1^b. Then the lower hanger member is quickly lowered so as to free the latch member 8 from engagement with the tubular member 7, whereupon the parts carried by the spring wire members 28 will again rock upwardly so as to assume an upwardly extending position, as shown in Fig. 1^a.

Thus, it will be seen that I have provided not only an improved means for supporting the lower contacts and obtaining effective electric contact engagement of the same with the upper contacts, but I have furthermore provided such a means which at the same time maintains effective wiping engagement between the contacts during manipulation of the lower hanger member while being engaged with and disengaged from the upper hanger member. I have furthermore provided contact members and supports for the same which are standardized to a certain extent and which can be readily removed and renewed, thereby increasing the efficiency without increasing the cost.

The specific contact supporting arms and contacts as here shown are merely for purposes of illustration, it being possible to adopt other forms of arms and contacts according to the principle and spirit of the 105 present invention.

What I claim is:—

1. A lamp hanger structure comprising a pair of releasably latchable hanger members, contactors fixed in opposed relation upon one of said hanger members, opposed springs each fixed at one end upon the other hanger member and extending transversely of the direction of latching movement, insulating means upon the free ends of said springs, and contactors carried by said insulating means and spaced to register with said first named contactors, said springs being adapted to flex and thereby produce movement of the contactors carried thereby transversely of the 110 direction of latching movement, whereby wiping movement between said pairs of contactors is effected during latching of said hanger members.

2. A lamp hanger structure comprising a 115 pair of releasably latchable hanger members, contactors fixed in opposed relation upon one of said hanger members, studs upon the other hanger member, springs having convolutions 120 engaging said studs and end portions abut- 125

ting said other hanger member and free end portions extending outwardly therefrom, insulating means upon said free end portions, contactors carried by said insulating means 5 and spaced to register with said first named contactors, said springs being adapted to flex and thereby produce movement of the contactors carried thereby transversely of the direction of latching movement, whereby wiping 10 movement between said pairs of contactors is effected during latching of said hanger members.

3. A lamp hanger structure comprising, a pair of vertically aligned hanger members releasably latchable by relative axial movement, a pair of contactors fixed upon the upper of said hanger members in oppositely spaced relation in an axial plane thereof, a pair of generally aligned and radially extending 15 springs secured upon the lower hanger member, each of said springs comprising a wire formed midway of its length with a generally horizontally extending loop, medially of said loop and each end of said wire with 20 a series of convolutions substantially in said axial plane, and with the ends of said wire extending from said convolutions in a direction generally tangent thereto, members on said lower hanger member extending within said convolutions to position said springs, said wire being provided with concave contacting surfaces, and those on said lower hanger member with convex 25 contacting surfaces, the proportions and arrangement of the parts of said structure being such that the wiping engagement of said contactors during said latching movement of said hanger members, includes relative movement from initial contacting position up to, beyond, and back to latched contacting position.

4. A lamp hanger structure comprising a pair of vertically aligned hanger members releasably latchable by relative axial movement, a pair of contactors fixed upon the upper of said hanger members in oppositely spaced relation in an axial plane thereof, a pair of generally aligned and radially extending 30 springs secured upon the lower hanger member, each of said springs comprising a wire formed midway of its length with a generally horizontally extending loop, medially of said loop and each end of said wire with 35 a series of convolutions substantially in said axial plane, and with the ends of said wire extending from said convolutions in a direction generally tangent thereto, members on said lower hanger member extending within said convolutions to position said springs, said wire ends of said springs abutting portions of said hanger member to maintain said spring loop portions normally extending from said convolutions upward, insulating 40 members secured in said loops, and contactors secured in said insulating members, said last named contactors being spaced correspondingly with said fixed contactors and adapted to yield in said axial plane by flexure of said 45 springs with arcuate movement, whereby wiping engagement between said pairs of contactors is effected during latching movement of said hanger members, the contactors on said upper hanger member being provided with concave contacting surfaces, and those on said lower hanger member with convex 50 contacting surfaces.

5. A lamp hanger structure comprising a pair of vertically aligned hanger members releasably latchable by relative axial movement, a pair of contactors fixed upon the upper of said hanger members in oppositely spaced relation in an axial plane thereof, a pair of generally aligned and radially extending 55 springs secured upon the lower hanger member, each of said springs comprising a wire formed (a) midway of its length with a

generally horizontally extending loop, (b) medially of said loop, and each end of said wire with a series of convolutions substantially in said axial plane (c) and with the ends of said wire extending from said convolutions in a direction generally tangent thereto, members on said lower hanger member extending within said convolutions to 60 position said springs, said wire being provided with concave contacting surfaces, and those on said lower hanger member with convex contacting surfaces, the proportions and arrangement of the parts of said structure being such that the wiping engagement of said contactors during said latching movement of said hanger members, includes relative movement from initial contacting position up to, beyond, and back to latched contacting position. 65

5. In a lamp hanger structure comprising a pair of releasably latchable hanger members, a contactor secured on one of said hanger members and having a contacting surface 70 arranged generally transverse to the direction of latching movement, spring means on the other hanger member and a contactor positioned on said spring means to abut said first named contactor when said hanger members are latched, said spring means being adapted to yield to impart generally arcuate movement to the contactor carried thereby as the hanger members are latched, to effect wiping of said sprung contactor across said 75 surface of said first named contactor, said sprung contactor having a contacting surface curved correspondingly with said yielding movement. 80

6. In a lamp hanger structure comprising a pair of releasably latchable hanger members, a contactor secured on one of said hanger members and having a concave face extending generally transverse to the direction of latching movement, spring means fixed at one 85 end and extending transversely to said direction on the other hanger member, and a contactor carried by said spring means and having a complementary convex face for seating against said first named contactor when said hanger members are latched, said spring means being yieldable to impart generally arcuate movement to the contactor carried thereby as the hanger members are latched, to effect wiping of the sprung contactor across the face 90 of said first named contactor. 95

In testimony whereof I hereby affix my signature.

ALLISON J. THOMPSON.
